CLAIM

The ornamental design for a pill, as shown and described.

DESCRIPTION

FIG. 1 is a top perspective view of a pill showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a bottom perspective view of another embodiment thereof, the top perspective, front, rear, left side, right side, and top views being identical to FIG. 1 and FIGS. 3-7;

FIG. 10 is a bottom view thereof;

FIG. 11 is a bottom perspective view of another embodiment thereof, the top perspective, front, rear, left side, right side, and top views being identical to FIG. 1 and FIGS. 3-7; and,

FIG. 12 is a bottom view thereof.

The broken lines depict portions of the pill which form no part of the claimed design.

1 Claim, 10 Drawing Sheets
